UNITED STATES PATENT OFFICE.

THOMAS P. GREGER, OF PHILADELPHIA, PENNSYLVANIA.

DESIGN FOR A MANHOLE-COVER.

SPECIFICATION forming part of Design No. 27,676, dated September 21, 1897.

Application filed August 4, 1897. Serial No. 647,134. Term of patent 14 years.

To all whom it may concern:

Be it known that I, THOMAS P. GREGER, a citizen of the United States, residing at the city of Philadelphia, in the county of Philadelphia and State of Pennsylvania, have invented and produced a new and original Design for Manhole-Covers, of which the following is a specification, reference being had to the accompanying drawings, forming a part thereof.

Figure 1 is a top or plan view of a manhole-cover showing my design, and Fig. 2 is a central longitudinal section, these two views being deemed necessary to fully illustrate my design.

The leading feature of my design consists in a concave manhole-cover having the spur-like and inclined ornaments arranged within the outline of the cover and all inclined toward the center of the cover in connection with a substantially horizontal beveled flange arranged around the inner edge of the concavity and projecting above the floor of the cover.

Referring to the drawings, *a* is the floor of the cover, and *b* the periphery, forming with the floor in cross-section a substantially concave cover. Arranged within the periphery

of the cover and projecting angularly upward from the floor is a series of spurs or prongs *d*, each of which is inclined toward the center of the cover. These spurs or prongs are preferably arranged in concentric circles, as shown. Projecting inward from the periphery of the cover and arranged horizontally above the floor is an annular beveled flange *e*. Above the flange *e* the periphery *b* flares outwardly, as indicated at *f*. The cover when viewed in plan presents the appearance of a circular figure, within which is grouped one or more series of concentrically-arranged star-shaped prongs.

Having thus described my design, what I claim as new, and desire to secure by Letters Patent, is—

A design for manhole-covers, substantially as herein shown and described.

In testimony whereof I have hereunto set my signature in the presence of two subscribing witnesses.

THOMAS P. GREGER.
